DESIGN FOR A COMBINED SHAVING MUG AND BRUSH HOLDER

Charles Harvey Churchill, Cortland, N. Y.

Application February 9, 1944, Serial No. 112,599

Term of patent 14 years

(Cl. D86—10)

To all whom it may concern:

Be it known that I, Charles Harvey Churchill, a citizen of the United States, residing at Cortland, in the county of Cortland and State of New York, have invented a new, original, and ornamental Design for a Combined Shaving Mug and Brush Holder, of which the following is a specification, reference being had to the accompanying drawing, forming part thereof.

The figure is a perspective view of a combined shaving mug and brush holder, showing my new design.

The other side of the article, not shown, is substantially the same as the side shown.

I claim:

The ornamental design for a combined shaving mug and brush holder, as shown

CHARLES HARVEY CHURCHILL,
